CLAIM

The ornamental design for an earphone charging case, as shown and described.

DESCRIPTION

FIG. 1 is a top, front perspective view of an earphone charging case, showing our new design.

FIG. 2 is a front elevation view thereof.

FIG. 3 is a back elevation view thereof.

FIG. 4 is a right side elevation view thereof.

FIG. 5 is a left side elevation view thereof.

FIG. 6 is a top plan view thereof; and,

FIG. 7 is a bottom plan view thereof.
